UNITED STATES PATENT OFFICE.

EDWARD PARUSZEWSKI, OF KOTTBUS, GERMANY.

APPARATUS FOR KNOTTING PILE-THREADS.

No. 921,446.

Specification of Letters Patent.

Patented May 11, 1909.

Application filed February 28, 1908. Serial No. 418,378.

To all whom it may concern:

Be it known that I, EDWARD PARUSZEWSKI, a subject of the German Emperor, residing at 70 Bahnhofstrasse, Kottbus, Germany, 5 have invented certain new and useful Improvements in Apparatus for Knotting the Pile-Threads in the Manufacture of Smyrna Carpets and Like Fabrics; and I do hereby declare the following to be a full, clear, and 10 exact description of the invention, such as will enable others skilled in the art to which it appertains to make and use the same.

The present invention relates to an apparatus for knotting the pile threads in the 15 manufacture of Smyrna carpets and like woven fabrics.

According to the invention two threads are raised from the warp by a barbed needle and are separated to bring them one on each 20 side of a knotting tweezers; a carrier then lays a pile thread across them and a presser brings the two warp threads together and folds the pile thread over them, so that the ends of the pile thread can be seized by the 25 tweezers which then draw these ends between the two warp threads.

A suitable apparatus for practicing the invention is illustrated in the drawings, in which:

30 Figure 1 is a side-elevation, partly in section, of a loom constructed according to the invention, Fig. 2 is a detail front-elevation of one side of the loom, Fig. 2^a is a similar elevation of the other side or half of the 35 loom, showing the knotting mechanism, Fig. 3 is a detail perspective view showing the manner in which the knot is formed, Figs. 4 and 5 are a side-elevation and vertical section respectively through the knotting tweezers and their operating mechanism, Fig. 6 is 40 a detail elevation of the needle for withdrawing and separating two threads from the warp, Fig. 7 is a side-elevation of Figs. 6, and Figs. 8 and 9 are a side and front elevation 45 respectively of the conveyer mechanism for carrying the cut pile-threads to the knotting devices.

The ground fabric is produced in the known manner on an ordinary loom having 50 two shafts.

1 is the warp, 2 the pile threads (Figs. 2^a, 3, 8, and 9). The latter are led through perforations in a shield 3 and are drawn forward by pincers 4 (Figs. 1, 2^a and 9) in the 55 known manner; that is to say, according to

the position of the shield 3, which turns and slides on a shaft 5, the thread of the correct color comes opposite the pincers 4 and these are at that moment operated by a suitable mechanism to grip the thread and to draw 60 it some distance through the shield.

In order to convey the piece of thread, which is cut off in the usual manner by scissors 6, to the knotting device, according to the present invention, two conveyer bands 7 65 (Figs. 1, 2^a, 8 and 9) traveling on rollers 8 and 9, are provided with spring clamps 10 two of which as the bands travel grip the thread 2 and convey it downward. Shortly before the thread thus held arrives at the 70 lowest part of its course, a needle consisting of two parts 11 and 12 connected after the manner of scissor blades (Figs. 1, 6 and 7) is moved downward. This needle is formed at its lower end as a barbed hook, so that when 75 its parts are closed together, it can be thrust unhindered between two adjacent threads of the warp 1. The pin 14 on which the two parts of the needle are pivoted is fixed to a bar 19 which slides in the frame 15. The 80 upper portions of the parts 11 and 12 have outwardly curved slots 16 and 17 in which engages a pin 18 fixed to the frame. When the bar 19 is moved downward the pin 18 acting in the slots 16 and 17 first opens the 85 needle, but closes it again before it is thrust into the warp (Fig. 6). When the bar 19 moves upward again the needle engages by its barbed point 13 two warp threads and raises them as shown in Figs. 1, 3 and 6. In 90 the middle of its upward movement the needle is again opened by the action of pin 18 in slots 16 and 17, so that the two warp threads are held apart. At this moment clamps 10 on the conveyer bands 7 (Fig. 1) lay the pile 95 thread across the two warp threads. While the needle completes its upward stroke a presser 20 (Figs. 1, 2^a, 7 and 9) presses the two warp threads together at the place where the pile thread has been laid, thus at 100 the same time folding the two ends of the pile thread downward over the two warp threads. During this operation the knotting tweezers 21 (Figs. 1, 4 and 5) approach the pile thread. This device is carried by an oscillating lever 22 and consists of a small tube 24, mounted to turn in brackets 23 on the lever 22, and a bolt 25 adapted to revolve in this tube. The tube and bolt each has at its lower end a semi-cylindrical pin 26, 27 which 110

pins form the jaws of the tweezers. The tube 24 also carries a pin 28 and on the bolt 25 is a pin 29. These pins engage respectively in slots 30 and 31 of a lever 32 centered on the pin 34 carried by a bracket 33 on the lever 22; a spring 35 keeps lever 32 against a stop 36.

When the lever 22 is advanced, the upper end of lever 32 strikes against a lever 37 centered on the frame of the machine (Figs. 1, 4 and 5) and normally pressed against a fixed stop 39 by a spring 38. By striking this lever 37, the lever 32 is turned on its center 34 against the action of spring 35, and owing to the engagement of the pins 28 and 29 in the slots 30 and 31, the tube 24 and the bolt 25 are turned in opposite directions and the jaws 26 and 27 are opened, Fig. 9. The hanging ends of the pile thread 2 are now between these jaws. The upper end of the lever 32 now slips past lever 37 and the lever 32 returns to its normal position in which it is held against the stop 36 by action of spring 35. Thus the jaws of the tweezers close again and grip the ends of the pile thread. The lever 22 now returns and the incline 40 of lever 32 strikes against the incline 41 on lever 37. In this movement the lever 32 is prevented from turning by the stop 36, while the lever 37 moves out of the way. The jaws 26, 27 remain closed and moving as indicated in Fig. 3 between the two warp threads, draw the pile thread 2 toward the work. At the same time the needle 13 has arrived at its highest position, and the warp threads are thrown off the needle by contact with the pointed lower end of the frame 15. The ends of the pile thread which have been drawn upward above the two warp threads, now drop out of the tweezers 21. The nap is now knotted and the whole arrangement is advanced a step forward by suitable gear to knot the pile thread in the next two warp threads.

45 The various movements described are derived from cams keyed on the shaft 42 (Fig. 2^a).

The whole knotting apparatus is mounted on cross beams 43 which can swing in the frame on pin 44, as shown in Fig. 2 so that the apparatus can be displaced to allow the batten to pass.

Having thus described my invention, I claim:

55 1. In a loom for weaving pile-fabrics, means to raise two adjacent threads from the warp comprising a vertically movable needle formed of two pivoted parts.

2. In a loom for weaving pile-fabrics, means to raise two adjacent threads from the warp comprising a vertically movable needle formed of two pivoted parts and having a barbed end.

3. In a loom for weaving pile-fabrics, means to raise certain of the threads from the

warp comprising a needle composed of two separate thread-carrying parts, and means to spread said parts to separate the threads.

4. In a loom for weaving pile-fabrics, a vertically movable separating needle having 70 a barbed end and composed of two pivoted parts, and means to spread said parts when the needle is raised and bring them together when the same is lowered.

5. In a loom for weaving pile-fabrics, a 75 separating needle composed of two pivoted parts having curved slots, a fixed pin engaging said slots, and means to raise and lower the needle.

6. In a loom for weaving pile-fabrics, 80 means to cut the pile-threads, and means to carry the cut threads to the knotting devices, comprising an endless conveyer.

7. In a loom for weaving pile-fabrics, means to cut the pile-threads, and means to 85 carry the cut threads to the knotting devices, comprising an endless conveyer having clamps to grip the cut pile-threads so that the latter after being cut are carried along by the conveyer.

8. In a loom for weaving pile-fabrics, means to cut the pile-threads, and parallel bands carrying clamps by which the ends of the cut threads are grasped and the thread carried along to the knotting devices. 95

9. In a loom for weaving pile-fabrics, means to cut the pile-threads, parallel conveyer-bands across which the cut threads extend transversely, and clamps on said bands by which the ends of the cut threads are 100 grasped, such threads being carried at each end by a different band.

10. In a loom for weaving pile-fabrics, knotting tweezers comprising a bolt forming one member of the tweezers, a tube inclosing 105 the bolt and forming the other member, and means to turn said parts in opposite directions comprising pins carried by the bolt and tube at opposite ends and a fulcrumed lever engaging said pins.

11. In a loom for weaving pile-fabrics, knotting tweezers comprising an inner bolt, an outer tube, a lever having an intermediate pivot and connected at one end with the bolt and at the other end with the tube, and 115 means to oscillate said lever.

12. In apparatus for knotting the pile threads in the manufacture of Smyrna carpets and like fabrics the combination of a barbed needle for withdrawing and separating two threads from the warp, a knotting tweezers, an endless conveyer for conveying a pile thread on to the two warp threads, means for pressing the ends of the pile thread and the two warp threads together 120 and means for causing the tweezers to seize the ends of the pile thread and draw them between the two warp threads.

13. In apparatus for knotting the pile threads in the manufacture of Smyrna car- 130

pets and like fabrics the combination of a barbed needle for withdrawing and separating two threads from the warp, a knotting tweezers, an endless conveyer provided with 5 clamps for conveying a pile thread on to the two warp threads, means for pressing the ends of the pile thread and the two warp threads together and means for causing the tweezers to seize the ends of the pile thread

and draw them between the two warp 10 threads.

In testimony, that I claim the foregoing as my invention, I have signed my name in presence of two subscribing witnesses.

EDWARD PARUSZEWSKI.
